UNITED STATES PATENT OFFICE.

EDWARD THOMAS, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,274,106.

Specification of Letters Patent. Patented July 30, 1918.

Application filed January 4, 1917. Serial No. 140,488.

To all whom it may concern:

Be it known that I, EDWARD THOMAS, a citizen of the United States, residing in New York city, in the county of New York 5 and State of New York, have invented certain new and useful Improvements in Type-Writing Machines, of which the following is a specification.

This invention relates to revoluble platen 10 typewriting machines, in which provision is made for collating work-sheets of various sizes and shapes in various relative positions, preparatory to making simultaneous original and carbon type impressions on the col- 15 lated sheets.

In the Underwood typewriting machines now manufactured for this purpose, the sheets are collated by impaling them upon a pair of endless bands provided with studs, 20 to engage perforations or notches in the side edges of the work-sheets, and the collated sheets are advanced by means of said bands which run around the platen; the bands extending for considerable distance 25 away from the platen to give room for collating sheets.

According to one form of my present invention, the sheets may be collated upon a table in their natural reading positions, that 30 is, face up and with the bottoms of the sheets nearest the operative, and the use of the bands thus rendered unnecessary.

In carrying out the invention in the form herein disclosed, the platen of an Under- 35 wood front-stroke typewriting machine is lifted bodily by bringing the rear side there- of to the top, and the sheets are then laid upon the table, which is adjacent to the ele- vated platen, with the faces of the sheets 40 uppermost and with the leading edges of the sheets lying upon the platen, and advanced far enough to be grasped by the platen feed rolls; the latter being released during the collating of the sheets. Upon said table 45 are placed studs advantageously in two rows, one row along each side of the table, on which studs the sheets are impaled by means of the usual notches or perforations on the side edges. These studs are preferably dis- 50 appearing, so that after the sheets are col- lated, the studs are withdrawn as soon as such sheets are clamped to the platen by the rolls, thus avoiding danger of accidental dis- arrangement when transferring them from 55 the control of the studs to the control of the

platen feed rolls. The studs having been withdrawn, the collated sheets are now free to be advanced around the platen independ- 60 ently of the studs. In practice, the platen, while still elevated, may be rotated to ad- vance the sheets around in the rear of and forwardly under the platen.

Before dropping the platen to working position, a flap may be closed down upon the sheets; said flap preferably comprising two 65 parts hinged one upon each side of the col- lating table so that they can be swung up for the collating operation.

At the operation of dropping the platen to its working position, the collating table 70 and its flap move with the platen; the latter preferably swinging from its upper collat- ing position to its lower printing position, and the collating table and its flap swinging therewith; the movement of the table be- 75 ing upwardly and backwardly, and finally assuming preferably a standing position with a rearward inclination. The surface of the table and the flap or flaps, then form a table along which the collating sheets may 80 advance as they are fed line-by-line by a typewriting operation.

Since some of the sheets may be too short to reach to the platen at the collating opera- 85 tion, there are preferably provided upon the flaps, auxiliary feeding devices to press the sheets together sufficiently to make them ad- vance properly at the platen rotating opera- 90 tion. These feeding devices may be in the form of rolls mounted at intervals along the table to keep control of the short sheets after 95 the studs have been withdrawn, and until they reach the bite of the platen and its feed roll, which will be in some cases during the preliminary rotation of the platen, or before the latter has dropped to its printing position, and in some cases, after the actual printing operation has been done, and dur- 100 ing the line feeding movements of the platen.

Preferably the collating pins have a me- 100 chanical connection with the paper feed rolls which run upon the platen, so as to release said rolls when the collating pins or studs are projected to their working positions, and, subsequently, to restore said feed rolls 105 to working positions against the platen or the sheets thereon just before the collating studs relinquish their control of the collat- ing sheets; this may be effected either man- ually or automatically.

The revoluble platen of the Underwood typewriting machines are under the control of various line-spacing devices, including a line-space lever and pawl, and also including a detent and line-space wheel; and there is also provided a knob at each end of the platen, for rotating the platen indefinitely. It is desirable to keep the platen under control, not only when it is down in printing position, but also when it is up in collating position, and to be able to rotate the elevated platen by means of a knob and under the control of the detent and line-space wheel. It is preferable to elevate the platen, however, without disturbing the location of the above described line-spacing and platen rotating devices, and for this reason the line-space wheel, with the associated knob, is mounted upon the stud shaft in line with the platen axle, and preferably, the knob, at the opposite end of the platen, is fast on a corresponding stud shaft. These stud shafts have gears to mesh with a pair of pinions fixed upon the ends of the platen itself and correspond with the stud shaft gears. Hence, pairs of gears extend from the ends of the platen to the stud shafts, so that the platen is always under control, and may be rotated one or more definite line-space distances, and there retained the same as if the platen were down at printing position, and as if a single axle served for both the platen and the line-space wheel and knobs. Therefore, one of the features of the invention consists in the provision of a collating table which, together with the platen may swing up about the before-mentioned pinion shaft as a center to bring the table into collating position while the platen remains under the control of one or both knobs, and of the line-space wheel and detent, so that the platen may be rotated by the knob or knobs in line-space position, as required. The swinging up of the platen, it will be understood, brings the pressure rolls, which usually run upon the bottom of the platen, up to such a high position that the leading ends of the sheet can easily reach the same and occupy a position to be clamped thereby, without being too far advanced for collating purposes.

The paper shelf, which normally occupies a position at the rear of the platen, serves when the platen is swung up to collating position, as an introductory guide for the leading edges of the collating sheets, and may be made of celluloid or other transparent material, to enable the operative to see the sheets, and particularly to note whether they are within range of the platen feed roll.

This paper shelf may extend under the platen and up in front thereof when in printing position, and its ends may have upward extensions to direct the printing sheets upwardly and over the top of the platen and

between the surface of the platen and the pinion shaft, above referred to.

As the printing sheets advance up around the platen, they are deflected rearwardly by means of suitably curved wire fingers, and their leading edges then inclined back against the surface of the collating table; this being the surface which is underneath when the table is swung to collating position. 75

When the machine is in collating position, the leading edges of the sheets are directed by the wire or other guides, on to a third table, which is arranged upon the front of a typewriter carriage, and said sheets may advance along this table toward the front thereof and hang down in the front of the machine until the table and platen are swung back to working positions, when the advance edges of the sheets may be swung back 85 against the table, and then inclined upwardly and rearwardly.

The collating studs or pins on the table, may serve either to impale the sheets or as side gages therefor. A connection, ineffective on the studs in writing position, may be provided to release the feed rolls, and this may be operated by the same finger-piece as controls the studs. 90

Other features and advantages will hereinafter appear. 95

In the accompanying drawings,

Figure 1 is a side view largely sectional of my invention as applied to the carriage of an Underwood typewriting machine modified to some extent as shown in the patent to Wernery and Smith, No. 1,132,055. In this figure, the normal writing position of the parts is shown in full lines and the collating position of the platen and some other parts are shown in dotted lines. 100

Fig. 2 is a side view similar to Fig. 1, section being taken on line 2-2 of Fig. 3, but showing the parts only as in the collating position and with the collating studs projected and the feed-rolls thrown off. 110

Fig. 3 is a plan view of Fig. 2 showing three sheets adjusted on the collating board and one wing thrown into holding position while the other wing is still opened out. 115

Fig. 4 is a longitudinal section along the broken line 4-4 of Fig. 3.

Fig. 5 is a view similar to Fig. 1 from the opposite side, but showing the collating table partly moved backward to an upright position where the mechanism, which throws the feed rolls against the platen and retracts the collating pins, is just beginning to functionate. 120

Fig. 6 is a view similar to Fig. 5, but showing the collating table in writing position, the bottom feed rolls, however, being thrown off while the collating pins are in their ineffective or retracted position. 125

Fig. 7 is a detail view showing the con- 130

nection between the handle for throwing off the bottom feed rolls and the pin and the lever secured to the shaft controlling the projecting connections.

5 Fig. 8 is a view similar to Fig. 5, but showing all the parts restored to their normal or writing position.

Fig. 9 is an end view showing the principal parts seen in Fig. 1, together with the 10 connections for moving the line-space detent to ineffective position when the collating table is moved to collating position.

The carriage of the typewriting machine slides on the usual rails 1 and 2 being drawn 15 along by any suitable form of escapement, so that types 3 on type-bars 4 may print one after another at letter space intervals. If desirable, case-shifting mechanism may be used, which, however, is advantageously in 20 the form of a shiftable type-basket to avoid the weight of shifting the added weight of the collating devices, although the weight of said devices, according to the present invention, may be very much less than in 25 those hitherto employed. Upper and lower characters 5 and 6 are, therefore, formed on the type-block 3.

The typewriter carriage includes the usual rotatable platen 7, which, by connections 30 hereinafter described, is adapted to be rotated in line-space intervals by the usual line-space handle or lever 8 operating the slide 9, which through the pawl 10, turns the line-space detent wheel 11. In order to 35 accurately align the platen at line-space intervals, the usual line-space detent 12 is provided to coöperate with the line-space wheel 11. In order that the line-space wheel 11 may rotate the platen, said wheel is fixed to 40 a stub shaft 13, provided with the usual knob 14 and journaled in the frame 15 of the carriage, and said stub shaft is geared level to the platen, so that any rotation of the line-space wheel will rotate the platen a 45 precisely equal amount. The gearing between the shaft 13 and the platen 7 includes a gear wheel 16 fast on the stub shaft 13, and an identical gear wheel 17 fast on an extension 18 of the platen axle 19, said axle 50 being journaled at each end in a supplementary swing frame 20. In order that the two gear wheels 16 and 17 may rotate together, they mesh with a single broad pinion 21, which is journaled above and in front of the 55 platen 7. In order that the two ends of the platen may always move together, the opposite end of the platen axle 19 is similarly journaled in the swing frame 20 and is geared to a stub shaft 19 carrying a knob 60 14 (not shown), the connection between the stub shaft 19 and the platen shaft 18 including pinions 16, 17 and 21, which are identical with the other pinions above-mentioned. The two pinions 21 are fast on a 65 common shaft 23, which is journaled in the

carriage frame 15, and serves as a journal on which the swing frame 20 swings. The shaft 23 is provided with a sleeve 24, which forms part of the swing frame 20. The swing frame 20, according to the present 70 invention, not only carries the platen 7, but also carries the usual front and rear pressure rolls 25 and 26, and a paper apron 27, which occupies a position, when the platen is in writing position, approximately that of 75 the usual Underwood paper table and apron. For the purpose of writing, the platen occupies approximately the position of the platen in an ordinary Underwood typewriting machine, as shown in full lines in Fig. 1. 80 For the purpose of locking the platen in this position to enable writing to be accurately and neatly done, the swing frame 20 is adapted to be locked down by a pair of catches 28, which are located adjacent opposite ends of the swing frame 20, and are adapted to catch on studs 29 on said frame. In order to release these catches, there is provided at the left hand side of the machine, a handle 30 which forms an extension 90 on one of the catches 28, and is able to release both catches simultaneously because they are both fast on a common shaft 31, which is provided with springs normally tending to hold the catches 28 in effective 95 position over the studs 29.

When the catches 28 are released, the swing frame 20 may be swung up, thus carrying or rotating a collating table 32, which is fast thereto, forwardly and downwardly 100 to a convenient position for the operative to adjust work-sheets thereon. In Fig. 2 this position is shown as horizontal, and at that angle collating board 32 is supported by resting on rubber-tipped bumpers 33 mounted 105 on the typewriter carriage.

While the collating table 32 is coming around to horizontal position, pins 35 (which may be of the usual Underwood collating type) are projected through the 110 collating table 32, and at the same time the feed rolls 25 and 26 are moved clear of the platen. This enables work-sheets 36, 37 and 38 to be adjusted on the collating table by using the pins 35 either as impaling pins to 115 project through perforations 39 in the work sheets, or enables the pins 35 to be used as side or end gages for adjusting said sheets. In thus adjusting them, one or more of the sheets may project under the apron 27, 120 which may be made of celluloid to be transparent for convenience, and the sheets may project farther past the rolls 25 and 26 around under the platen and out over wire paper-guides 40, which rise from in 125 front of the normal position of the platen past around and behind the sleeve 24, and then forwardly to the front of the typewriter carriage, thus making it impossible for the leading edge of the work-sheets to 130

fall down between the platen and the front rail of the machine. These wire-guides 40 are partly supported by a light bar or wire 41, which is fast on the carriage frame 15 near the front ends thereof and extends across the front of the carriage in front of the sleeve 24, and under the wire-guides 40. The wire-guides 40 are further supported at the front of the carriage by a second light bar 42, which is mounted on the usual front bar of the carriage, rising therefrom at the ends and being bent so that it passes under the fingers 40. The apron 27 is provided with fingers 43 which rise above the printing line and near each end of the platen and substantially in line with the pins 35. These fingers 43 rise up high enough to guide the edges of the work-sheets above the ends of the paper guides 40, where they are adjacent to the platen. Since these long fingers lie outside of the printing zone of the platen, they do not interfere with the printing, although they lie considerably above the printing line. In addition to the work-sheets 36, 37 and 38 described above, there may also be inserted interleaved carbon sheets 44.

As was mentioned above, the bringing forward of the collating table 32 into collating position, automatically releases the feed-rolls 25 and 26 and simultaneously projects the pins 35. To accomplish this, there is provided on the side of the typewriter carriage frame a forwardly and upwardly extending cam 45, in which runs an impaling pin operating follower 46, which forms part of a slide 47, said slide being provided with slots 48 and 49, which slide respectively on pins 50 and 51, which, in turn, are respectively mounted on the swing frame 20 of the carriage, and on a bracket 52 fast on the collating table 32. The pulling forward of the collating table causes the follower 46 to be thrust upwardly along the collating table rather rapidly, so that by the time the collating table has reached the vertical position seen in Fig. 5, the impaling pins are projected and the feed-rolls 25 and 26 are thrown off. The connections between the slide 47 and the impaling pins 35 which enable them to be thus thrown off, include a rack bar 53, which is formed as a bracket extension of the slide 47, said rack bar meshing with a pinion 54 fast to a shaft 55, which is journaled at opposite ends of the brackets 52, which are fast to the collating table 32, and this shaft carries pinions 56 and 57 which mesh with corresponding rack bars 58 and 59 to insure a parallel motion of the pin-projecting slides 60, which will now be described. The pin-projecting slide 60 slides on the collating table 32, being provided for this purpose with slots 61 and 62, which slide respectively on a shouldered pin 63 fast in a lug 64 on the bottom of the collating table 32, and on a shouldered pin 65

fast on a U-shaped projection 66, of the collating table near the platen. When this slide is moved away from the platen, diagonal cam slots 67 therein cam outwardly the pins 68, which are fast on the bars 69, said bars serving as mounts for the pins 35, thus the sliding of the slide bar 60 outwardly projects the pins 35, and its return positively withdraws them. There is a bar 69 for each row of pins 35, and as will be seen from Fig. 4, each slide 60 controls a bar 69. For the purpose of covering up some of the mechanism, the outer surface of the slide 60 at the outer end of the collating table is turned up to bear against the under surface of the table 32. In order that the projection and withdrawal of the pins may simultaneously release and clamp respectively the feed-rolls 25 and 26, the feed-rolls are provided with the usual mounting on the usual shaft 70 of the Underwood feed-rolls, which, however, in the present instance, swings with the swingable frame 15. The usual roll release flat sided cam bar 71 is also provided, said bar being adapted to be operated by the usual rock arm 72. To cause the roll release cam bar 71 to be operated when the pins 35 are thus projected, there is provided a link 73, which is connected to be operated by the shaft 55. To operate the link 73, there is provided therein a slot 74, which is engaged by a pin 75 projecting from the arm 72, with the result that the moving of the pin control slide 60, will shift the feed-rolls 25 and 26 into and out of their seizing position.

In order to hold the work-sheets against the collating table 32, when it is swung from the collating position up to writing position, there are provided side flaps 76 hinged at each side of the collating table 32, and adapted when swung down to effective position against the work-sheets (see the left-hand or upper flap, Figs. 3 and 4) to bear against said work-sheets by means of feed-rolls 77. These rolls allow the top work-sheet 36 to slide easily, so that the drawing of it along by the bottom work-sheet 38, will cause the two work-sheets to travel together, because of the small friction between the top work-sheet and the rolls 77, which holds it in place. These flaps 76 are, for purposes of lightness and stiffness, made of light sheet metal with large portions thereof cut away and the edges 78 of the cutaway portions turn up to form stiffening webs. The flaps 76 are also provided with openings 79, registering with the pins 35 so that they may be folded down while the pins 35 are still projected. The flaps 76 extend down nearly as far as, but advantageously not quite to the paper apron 27; thus serving to keep the work-sheets practically under continuous control of one or the other set of feed-rolls, the feed-rolls for this purpose being set closer together than the minimum.

length of any work-sheet likely to be used. If it be desired to withdraw a work-sheet, while the collating table is in writing position, a handle 80 may be drawn upwardly and forwardly from the position seen in Fig. 8 to the position seen in Fig. 6. This handle is so connected to the rest of the mechanism that it casts off the feed-rolls 25 and 26 but is ineffective to project the impaling pins 35 when the collating board is in the Fig. 8 or writing position. For this purpose, a handle 80 is journaled near the end of the shaft 55, and moves against the tension of a spring 81, one end of which is fastened to the arm 72 the other end being fastened to a rock arm 82 fixed to the shaft 55. To release the feed-rolls the handle is moved from the Fig. 8 position to the Fig. 6 position where the handle has moved against the tension of the spring 81 to be arrested by a pin 82^a on the rock arm 82 and has been effective to move the feed-rolls away from the platen but has not been effective to rotate the shaft 55 to retract the pins 35. From the above description, it will be seen when the table is thrown to collating position, that the rotating of the shaft 55 by the follower 46 not only positively projects the impaling pins 35 but also positively throws off the feed-rolls 25 and 26, and when the table is already in collating position the handle may be effective to throw off the feed-rolls and project the pins and vice versa, but when the table is in writing position the handle 80 is effective only to throw off the feed rolls. The handle 80 it will be noted, is an extension of the arm 72 which carries the pin 75 of the pin-and-slot connection 74.

The feed-rolls 25 and 26 in the Underwood machine it will be remembered, are normally spring pressed against the platen, and in the present invention to return these feed-rolls against the platen when in writing position, there is the spring 81 between the handle 80 and the arm 82 which normally holds lug 83 against the arm 72 and tends to make the two move together. With the assistance of the springs which normally press the feed-rolls 25 and 26 against the platen, this spring is strong enough to return the feed-rolls against the platen. The spring 81 is however unable to project the impaling pins when the collating table is in writing position, owing to the fact that the follower 46 is positively held by its cam 45 with which it engages when in the writing position of the collating table.

In order that the feed-rolls 77 and the wings 76 which carry them may be detained strongly, either in their open or their closed position, the wings are provided with strong flat springs 85 which in the open position of the wings bear against the flat portion 86 on the under side of the collating table,

as seen at the left-hand side of Fig. 4, and in their closed position bear against a flat side 87 of the upper portion of the collating table with the result that the springs 85 and the flat surfaces with which they co-act 70 form cam detents for detaining strongly the wings in either of their adjusted positions.

Since the swing table in swinging up to collating position carries the platen around the pinion 21, there is some planetary motion of the platen in coming to collating position which has the effect of carrying the writing point of the platen around backwardly thereof. There is of course the same planetary motion in the reverse direction 75 in returning the platen to writing position after collating thereon. In order to avoid any possibility of this planetary motion causing the adjusted sheets to be fed around the platen so rapidly as to tear them on the 80 impaling pins 35, there is provided a device for automatically releasing the platen from its line-space detent so that the platen may be rotated by the work-sheet, in case the work-sheet is held too long by the pins 35. 90 To effect this result the ordinary Underwood line-space detent 12 (Fig. 9) is provided with the usual silencing cam 89 and this cam is automatically shifted to silencing position whenever the collating table 32 is 95 shifted out of normal writing position. To effect this, the silencing cam 89 is normally under tension of a spring 90 which tends to draw it up to silencing position, but said spring 90 is normally ineffective, because a 100 depending arm 91 fast on the swing frame 20 depresses the silencing cam 89 into its normal ineffective position against the tension of its spring 90 whenever the collating table is standing in writing position. The 105 normal writing position is shown in full lines in Fig. 9 and the silencing position of the detent 88 is shown in dotted lines therein.

As will be seen in Fig. 4, part of the platen swing frame extends as at 92 under 110 the wings 76 and serves to prevent them from falling down into a dependent position.

Variations may be resorted to within the scope of the invention, and portions of the improvements may be used without others: 115

Having thus described my invention, I claim:

1. In a typewriting machine, the combination with a revoluble platen, of a carriage in which said platen is mounted, feeding devices for advancing a work-sheet around the platen and from the rear of the machine to the front thereof, devices for supporting the work-sheets at the rear of the platen, a collating table, a swing frame in which 120 said collating table and said platen are both mounted, and a mounting for said platen and said collating table to enable them to be swung to a position where work-sheets may be adjusted face side up and bottom to the 125 130

operator to be later automatically delivered by said table to said platen.

2. In a typewriting machine, the combination with a revolute platen, of a carriage in which said platen is mounted, devices for supporting the work-sheets at the rear of the platen, a collating table, a swing frame in which said collating table and said platen are both mounted, a mounting for said platen and said collating table to enable them to be swung to a position where work-sheets may be adjusted, face side up and bottom to the operator to be later automatically delivered by said table to said platen, and feed-rolls normally coöperating with said platen and swinging therewith and adapted to clamp the work-sheets against the platen when adjusted on said table.

3. In a typewriting machine, the combination with a revolute platen, of a carriage in which said platen is mounted, feeding devices for advancing a work-sheet around the platen and from the rear of the machine to the front thereof, devices for supporting the work-sheets at the rear of the platen, a collating table, a swing frame in which said collating table and said platen are both mounted, a mounting for said platen and said collating table to enable them to be swung to a position where work-sheets may be adjusted, face side up and bottom to the operator to be later automatically delivered by said table to said platen, collating gages forming part of said collating table, and means for making said gages ineffective at will.

4. In a typewriting machine, the combination with a revolute platen, of a carriage in which said platen is mounted, devices for supporting the work-sheets at the rear of the platen, a collating table, a swing frame in which said collating table and said platen are both mounted, a mounting for said platen and said collating table to enable them to be swung to a position where work-sheets may be adjusted, face side up and bottom to the operator to be later automatically delivered by said table to said platen, feed-rolls normally coöperating with said platen and swinging therewith and adapted to clamp the work-sheets against the platen when adjusted on said table, collating gages forming part of said collating table, and means for making said gages ineffective at will.

5. In a typewriting machine, the combination with a revolute platen, of a carriage in which said platen is mounted, devices for supporting the work-sheets at the rear of the platen, a collating table, a swing frame in which said collating table and said platen are both mounted, a mounting for said platen and said collating table to enable them to be swung to a position where work-sheets may be adjusted face side up and bot-

tom to the operator to be later automatically delivered by said table to said platen, feed-rolls normally coöperating with said platen and swinging therewith, and adapted to clamp the work-sheets against the platen when adjusted on said table, and additional feed-rolls adapted to press work-sheets against said table and also adapted to remain ineffective at will.

6. The combination with a revolute platen, of a collating table adapted to deliver work-sheets to said platen, releasable feed-rolls adapted to hold work-sheets against said collating table, and a swinging frame in which said platen is journaled normally holding said collating table at the rear of the platen and adapted to swing it and the platen forwardly.

7. The combination with a platen and a swing frame therefor adapted to swing the platen up and away from the printing point, of a paper apron swinging with the platen, a collating board swinging into position to deliver sheets to the platen, face up and with their bottom to the operator, and fingers for guiding the paper from said apron up beyond the printing point while the platen is swung away therefrom.

8. The combination with a platen and a swing frame therefor adapted to swing the platen up and away from the printing point, of a paper apron, a collating board swinging into position to deliver sheets to the platen, face up and with their bottom to the operator, fingers for guiding the paper from said apron up beyond the printing point, a carriage of which said platen and board form a part, a front rail in front of said carriage on which the carriage travels, and paper guides extending from the platen and below the printing point up and over said carriage, where it travels along the rail.

9. The combination with a traveling carriage and a rotatable platen, of a collating table therefor traveling with said platen, means for supporting said collating table so that it may be swung down between the platen and the operative to enable the adjusting of work-sheets thereon, and feed-rolls adapted to be raised from said collating table to permit work-sheets to be adjusted thereon and adapted to rest against said table to support work-sheets thereagainst, when the collating table is swung rearwardly.

10. In a typewriting machine, the combination with a traveling carriage, of a revolute platen therein, releasable feed-rolls beneath said platen, and means for supporting said platen to swing it and its feed-rolls to bring the feed-rolls up and behind the platen to enable a work-sheet to be adjusted over the platen with its leading edge beneath a feed-roll when released.

11. In a typewriting machine, the combi-

nation with a traveling carriage, of a revolute platen therein, feed-rolls beneath said platen, means for supporting said platen to swing it and its feed-rolls to bring the 5 feed-rolls up and behind the platen to enable a work-sheet to be adjusted over the platen when so thrown off, with its leading edge beneath a feed-roll, and means for making said feed-rolls effective or ineffective to 10 hold work-sheets while in said upward position.

12. In a typewriting machine, the combination with a traveling carriage, of a revolute platen therein, feed-rolls beneath said 15 platen, means for supporting said platen to swing it and its feed-rolls to bring the feed-rolls up and behind the platen to enable a work-sheet to be adjusted over the platen when so thrown off with its leading edge 20 beneath a feed-roll, means for making said feed-rolls effective or ineffective to hold work-sheets while in said upward position, and a paper apron and paper fingers adapted to guide the adjusted work-sheet around 25 the platen and beyond the printing point.

13. In a typewriting machine, the combination with a rotatable platen, of a traveling carriage, a swing frame, a line-space mechanism, means for gearing said platen 30 to said line-space mechanism so that the platen may be swung in the swing frame and remain geared to the line-space mechanism, and releasable feed-rolls for said platen forming part of said swing frame.

35 14. In a typewriting machine, the combination with a rotatable platen, of a traveling carriage, a swing frame, a line-space mechanism, means for gearing said platen to said line-space mechanism so that the 40 platen may be swung in the swing frame and remain geared to the line-space mechanism, releasable feed-rolls for said platen forming part of said swing frame, and a handle shiftable with said frame for controlling 45 said feed-rolls.

15. In a typewriting machine, the combination with a rotatable platen, of a traveling carriage, a swing frame, a line-space mechanism, means for gearing said platen 50 to said line-space mechanism so that the platen may be swung in the swing frame and remain geared to the line-space mechanism, releasable feed-rolls for said platen forming part of said swing frame, a collating 55 board forming part of said swing frame, impaling pins forming part of said collating board, and a handle forming part of said swing frame for simultaneously controlling said pins and said feed-rolls.

60 16. In a typewriting machine, the combination with a traveling carriage, comprising a revolute platen, of feed-rolls coöoperating with said platen, a swinging frame forming part of said carriage, in which said platen 65 is mounted to swing the platen to bring the

feed-rolls up in the rear thereof, means for making said feed-rolls effective and ineffective, and a latch for holding said platen in its normal position for writing.

17. In a typewriting machine, the combination with a revolute platen, and a collating table for adjusting the work-sheets to feed them to the platen, of impaling pins forming part of the collating table, said table being shiftable from the collating position to writing position, and means for moving the pins to ineffective position by moving the table to writing position. 70

18. In a typewriting machine, the combination with a revolute platen and feed-rolls therefor, of devices for moving said feed-rolls to and from said platen, a collating table movable from writing position to collating position, and connections whereby the moving of the table to writing position 80 moves the feed-rolls against the platen. 85

19. In a typewriting machine, the combination with a revolute platen and feed-rolls therefor, of devices for moving said feed-rolls to and from said platen, a collating 90 table movable from writing position to collating position, connections whereby the moving of the table to writing position moves the feed-rolls against the platen, and impaling pins adapted to stand in effective 95 or ineffective position.

20. In a typewriting machine, the combination with a revolute platen and feed-rolls therefor, of devices for moving said feed-rolls to and from said platen, a collating table movable from writing position to collating position, connections whereby the moving of the table to writing position moves the feed-rolls against the platen, impaling pins adapted to stand in effective or 100 ineffective position, and means whereby the moving of the table in writing position makes the feed-rolls effective and the impaling pins ineffective. 105

21. In a typewriting machine, the combination with a revolute platen and feed-rolls therefor, of devices for moving said feed-rolls to and from said platen, a collating table movable from writing position to collating position, connections whereby 110 the moving of the table to writing position moves the feed-rolls against the platen, impaling pins adapted to stand in effective or ineffective position, means whereby the moving of the table in writing position makes 115 the feed-rolls effective and the impaling pins ineffective, and separate feed-rolls coöperating with said table adapted to be separately made effective and ineffective. 120

22. In a typewriting machine, the combination with a traveling carriage and a revolute platen therein, of a swinging frame on which said platen is mounted, a transparent paper apron forming part of the bottom and back of said frame, and means for swinging 125 130

said frame to bring the apron above the platen to enable the operative to adjust work-sheets onto the platen with the apron in sight from the front.

5 23. In a typewriting machine, the combination with a revoluble platen and a normally upstanding collating table on which to adjust work-sheets for said platen, of a mounting for said table permitting it to be 10 swung down for collating purposes, wings adapted to be swung away from said collating table to permit work-sheets to be adjusted thereon, and means for holding said wings against said collating table when 15 swung thereagainst to hold work-sheets in place.

24. In a typewriting machine, the combination with a revoluble platen and a normally upstanding collating table on which 20 to adjust work-sheets for said platen, of a mounting for said table permitting it to be swung down for collating purposes, wings adapted to be swung away from said collating table to permit work-sheets to be adjusted 25 ed thereon, means for holding said wings against said collating table when swung thereagainst to hold work-sheets in place, and feed-rolls forming part of said wings.

25. In a typewriting machine, the combination with a revoluble platen and a normally upstanding collating table on which to adjust work-sheets for said platen, of a mounting for said table permitting it to be 30 swung down for collating purposes, wings adapted to be swung away from said collating table to permit work-sheets to be adjusted thereon, means for holding said wings against said collating table when swung thereagainst to hold the work-sheets in 35 place, feed-rolls forming part of said wings, and separate feed-rolls separately releasable and adapted to hold the work-sheets against the platen to cause them to be fed there-around.

45 26. In a typewriting machine, the combination with a rotatable swing frame including a platen, of a line-space mechanism for said platen, means for keeping said platen constantly connected to said line-space mechanism, a detent forming part of said line-space mechanism, and means for making said detent ineffective when the platen is 50 swung on its swing frame.

27. In a typewriting machine, the combination with a rotatable swing frame including a platen, of a line-space mechanism for said platen, means for keeping said platen constantly connected to said line-space mechanism, a detent forming part of said line- 60 space mechanism, a cam device for making said detent ineffective, and a bar forming part of said swing frame for determining whether said cam shall make said detent ineffective or not.

65 28. In a typewriting machine, the com-

bination with a rotatable swing frame including a platen, of a line-space mechanism for said platen, means for keeping said platen constantly connected to said line-space mechanism, a detent forming part of 70 said line-space mechanism, a cam device for making said detent ineffective, and a frame forming a part of said swing frame for determining whether said cam shall make said detent ineffective or not. 75

29. In a typewriting machine, the combination with a revoluble platen and a collating table therefor shiftable from writing position to collating position, of releasable feed-rolls for said platen, withdrawable impaling pins for said table, means whereby the moving of the platen from writing position releases the feed-rolls and shifts the pins to effective position, and manual means for releasing the feed-rolls while in writing 85 position.

30. In a typewriting machine, the combination with a revoluble platen and a collating table therefor shiftable from writing position to collating position, of releasable 90 feed-rolls for said platen, withdrawable impaling pins for said table, means whereby the moving of the platen from writing position releases the feed-rolls and shifts the pins to effective position, manual means for 95 releasing the feed-rolls while in writing position, and separate releasable feed-rolls.

31. In a typewriting machine, the combination with a rotatable platen, of a traveling carriage, a swing frame, a line-space 100 mechanism, means for gearing said platen to said line-space mechanism so that the platen may be swung in the swing frame and remain geared to the line-space mechanism, releasable feed-rolls for said platen forming 105 part of said swing frame, a line-space detent forming part of said line-space mechanism, and means for moving said detent to ineffective position by swinging the swing frame. 110

32. In a typewriting machine, the combination with a revoluble platen, of a carriage in which said platen is mounted, feed-rolls for advancing a work-sheet around the platen from the rear of the machine to the 115 front thereof, devices for supporting the work-sheets at the rear of the platen, a collating table, a swing frame in which said collating table and said platen are both mounted, a line-space mechanism for said platen, means for swinging said platen and said collating table to a position where work-sheets may be adjusted face side up and bottom to the operator to be later automatically delivered by said table to said 120 platen, the feed-rolls normally co-operating with said platen and swinging therewith and adapted to clamp the work-sheets against the platen when adjusted on said table, additional feed-rolls adapted to press work- 125 130

5 sheets against said table and also adapted to remain ineffective at will, a line-space detent forming part of said line-space mechanism, and means for moving said detent to ineffective position by swinging the swing frame.

33. In a typewriting machine, the combination with a revoluble platen, of a carriage in which said platen is mounted, feed-
10 rolls for advancing a work-sheet around the platen from the rear of the machine to the front thereof, devices for supporting the work-sheets at the rear of the platen, a collating table, a swing frame in which said 15 collating table and said platen are both mounted, a line-space mechanism for said platen, means for swinging said platen and said collating table to a position where work-sheets may be adjusted, face side up
20 and bottom to the operator to be later automatically delivered by said table to said platen, the feed-rolls normally coöperating with said platen and swinging therewith and adapted to clamp the work-sheets
25 against the platen when adjusted on said table, collating gages forming part of said collating table, means for making said gages ineffective at will, a line-space detent forming part of said line-space mechanism, and
30 means for moving said detent to ineffective position by swinging the swing frame

34. In a typewriting machine, the combination with a revoluble platen, of a carriage in which said platen is mounted, feeding
35 devices for advancing a work-sheet around the platen and from the rear of the machine to the front thereof, a collating table, a swing frame in which said collating table and said platen are both mounted, a line-
40 space mechanism for said platen, means for swinging said platen and said collating table to a position where work-sheets may be adjusted face side up and bottom to the operator to be later automatically delivered
45 by said table to said platen, collating gages forming part of said collating table, means for making said gages ineffective at will, a line-space detent forming part of said line-space mechanism, and means for moving
50 said detent to ineffective position by swinging the swing frame.

35. In a typewriting machine, the combination with a revoluble platen, of a carriage in which said platen is mounted, feeding
55 devices for advancing a work-sheet around the platen from the rear of the machine to the front thereof, a collating table, a swing frame in which said collating table and said platen are both mounted, a line-space mech-
60 anism for said platen, means for swinging said platen and said collating table to a position where work-sheets may be adjusted, face side up and bottom to the operator to be later automatically delivered by said
65 table to said platen, feed-rolls normally co-

operating with said platen and swinging therewith and adapted to clamp the work-sheets against the platen when adjusted on said table, a line-space detent forming part of said line-space mechanism, and means for 70 moving said detent to ineffective position by swinging the swing frame.

36. In a typewriting machine, the combination with a traveling carriage, a swing frame therein, a rotatable platen forming 75 part of said swing frame, a collating table forming part of said swing frame, collating pins and feed-rolls also forming part of said swing frame, a cam on said carriage, and means operated by said cam when said collating table is swung to collating position to properly position the pins and the feed-rolls.

37. In a typewriting machine, the combination with a traveling carriage and a 85 movable platen, of collating pins, and means for making said pins effective and ineffective by moving said platen.

38. In a typewriting machine, the combination with a collating board, of withdrawable collating pins for said board, means for withdrawing said pins and making them effective, a handle, and a one-way motion device between said handle and said means.

39. In a typewriting machine, the combination with a traveling carriage and a collating board swingable to collating position, of feed-rolls swingable therewith, manual means for casting off said feed-rolls irrespective of the position of said board, and a spring normally tending to make said feed-rolls effective.

40. In a typewriting machine, the combination with a traveling carriage including 105 a platen and a collating board therefor, of a swing frame including said platen and board, a hook at each end of said carriage for holding said frame in position, two rows of collating pins on said board, gearing for simultaneously projecting said pins, feed-rolls for said platen forming part of said frame, a shaft forming part of said gearing, and an arm fast to said shaft and comprising a lug for releasing said feed-rolls.

41. In a typewriting machine, the combination with a traveling carriage and a revoluble platen therein, of a collating-table for said platen adapted to deliver sheets to the rear side of the platen, a mounting for 120 said collating-table adapted to permit it to be swung forwardly, to permit work-sheets to be adjusted thereon, so that when the table is thrown back to its normal position, the work-sheets will be behind the table, 125 and devices moving with said table adapted to hold work-sheets in place against the table when the table is in its normal position, said devices adapted to be made ineffective when the table is in adjusting posi- 130

tion to permit work-sheets to be adjusted thereon.

42. In a typewriting machine, the combination with a traveling carriage and a revoluble platen therein, of a collating-table for said platen adapted to deliver sheets to the rear side of the platen, a mounting for said collating-table adapted to permit it to be swung forwardly, to permit work-sheets to be adjusted thereon, so that when the table is thrown back to its normal position, the work-sheets will be behind the table, devices moving with said table adapted to hold work-sheets in place against the table when the table is in its normal position, said devices adapted to be made ineffective when the table is in adjusting position to permit work-sheets to be adjusted thereon, normally ineffective collating-pins forming part of said table, and means for making said pins effective by swinging the table to adjusting position.

43. In a typewriting machine, the combination with a traveling carriage and a revoluble platen therein, of a collating-table for said platen adapted to deliver sheets to the rear side of the platen, a mounting for said collating-table adapted to permit it to be swung forwardly, to permit work-sheets to be adjusted thereon, so that when the table is thrown back to its normal position, the work-sheets will be behind the table, devices moving with said table adapted to hold work-sheets in place against the table when the table is in its normal position, said devices adapted to be made ineffective when the table is in adjusting position to permit work-sheets to be adjusted thereon, releasable feed-rolls for said platen, and means for automatically releasing said rolls by swinging said table to adjusting position.

44. In a typewriting machine, the combination with a traveling carriage and a revoluble platen therein, of an upstanding collating-table adapted to deliver work-sheets to the rear of said platen, a mounting for said table to permit it to be swung forwardly and downwardly, to permit work-sheets to be adjusted on the back thereof, guiding devices adapted to guide work-sheets from the end of the table around to the front of the platen when being adjusted, and holding devices mounted on the table adapted to be swung clear of the table to permit the adjustment of work-sheets, and adapted to be swung against the table to hold work-sheets thereon when in writing position.

45. In a typewriting machine, the combi-

nation with a revoluble platen, of a carriage in which said platen is mounted, feeding devices for advancing a work-sheet around the platen, and from the rear of the machine to the front thereof, a collating-table for delivering work-sheets to the rear of the platen, a swing frame in which said collating-table is mounted to enable it to be swung horizontally to adjust work-sheets thereon, and devices mounted upon said table adapted to be swung clear thereof to permit the adjustment of work-sheets, and to be swung against the table to hold work-sheets thereagainst while the table is being swung to writing position.

46. In a typewriting machine, the combination with a revoluble platen, of a carriage in which said platen is mounted, feeding devices for advancing a work-sheet around the platen, and from the rear of the machine to the front thereof, a collating-table for delivering work-sheets to the rear of the platen, a swing frame in which said collating-table is mounted, to enable it to be swung horizontally to adjust work-sheets thereon, and devices mounted upon said table adapted to be swung clear thereof to permit the adjustment of work-sheets, and to be swung against the table to hold work-sheets thereagainst while the table is being swung to writing position, said table also including impaling pins adapted to be effective when adjusting work-sheets, and automatically made ineffective by movement of the table to writing position.

47. In a typewriting machine, the combination with a traveling carriage and a revoluble platen therein, of a paper-table rising rearwardly from behind the platen and adapted to deliver sheets to the platen, and feed-rolls behind said table adapted to hold work-sheets against the back of said table while being fed upon the platen.

48. In a typewriting machine, the combination with a traveling carriage and a revoluble platen therein, of a paper-table rising rearwardly from behind the platen and adapted to deliver sheets to the platen, feed-rolls behind said table adapted to hold work-sheets against the back of said table while being fed upon the platen, and wings in which said feed-rolls are journaled, said wings pivoted on said table and adapted to be swung to and from said paper-table.
